(57) **CLAIM**

The ornamental design for a gripping base and drip guard for circular bottom container, as shown and described.

DESCRIPTION

FIG. 1 is a front view of a gripping base and drip guard for circular bottom container.

FIG. 2 is a first side view of the gripping base and drip guard for circular bottom container.

FIG. 3 is a second side view of the gripping base and drip guard for circular bottom container.

FIG. 4 is a back view of the gripping base and drip guard for circular bottom container.

FIG. 5 is a plan view of the gripping base and drip guard for circular bottom container.

FIG. 6 is a bottom view of the gripping base and drip guard for circular bottom container.

FIG. 7 is a first perspective view of the gripping base and drip guard for circular bottom container.

FIG. 8 is a second perspective view of the gripping base and drip guard for circular bottom container.

FIG. 9 is a first perspective view of section A-A of the gripping base and drip guard for circular bottom container.

FIG. 10 is a first side view of section A-A of the gripping base and drip guard for circular bottom container.

FIG. 11 is a second perspective view of section A-A of the gripping base and drip guard for circular bottom container.

FIG. 12 is a third perspective view of section A-A of the gripping base and drip guard for circular bottom container.

FIG. 13 is a fourth perspective view of section A-A of the gripping base and drip guard for circular bottom container.

FIG. 14 is a plan view of section A-A of the gripping base and drip guard for circular bottom container.

FIG. 15 is a front view of the gripping base and drip guard for circular bottom container containing an exemplary pail.

FIG. 16 is a first side view of the gripping base and drip guard for circular bottom container containing the exemplary pail.

FIG. 17 is a first perspective view of the gripping base and drip guard for circular bottom container containing the exemplary pail.

FIG. 18 is a second perspective view of the gripping base and drip guard for circular bottom container containing the exemplary pail.

FIG. 19 is a third perspective view of the gripping base and drip guard for circular bottom container containing the exemplary pail.

FIG. 20 is a front view of the gripping base and drip guard for circular bottom container containing an exemplary bucket.

FIG. 21 is a first side view of the gripping base and drip guard for circular bottom container containing the exemplary bucket.

FIG. 22 is a back view of the gripping base and drip guard for circular bottom container containing the exemplary bucket. FIG. 23 is a first perspective view of the gripping base and drip guard for circular bottom container containing the exemplary bucket.

FIG. 24 is a second perspective view of the gripping base and drip guard for circular bottom container containing the exemplary bucket.

FIG. 25 is a side view of section C-C of the gripping base and drip guard for circular bottom container containing the exemplary bucket.

FIG. 26 is a first perspective view of section C-C of the gripping base and drip guard for circular bottom container containing the exemplary bucket.

FIG. 27 is a second perspective view of section C-C of the gripping base and drip guard for circular bottom container containing the exemplary bucket.

FIG. 28 is a side view of section B-B of the gripping base and drip guard for circular bottom container containing the exemplary pail.

FIG. 29 is a first perspective view of section B-B of the gripping base and drip guard for circular bottom container containing the exemplary pail.

FIG. 30 is a second perspective view of section B-B of the gripping base and drip guard for circular bottom container containing the exemplary pail.

FIG. 31 is a first side view of the gripping base and drip guard for circular bottom container containing an exemplary propane tank.

FIG. 32 is a front view of the gripping base and drip guard for circular bottom container containing the exemplary propane tank.

FIG. 33 is a first perspective view of the gripping base and drip guard for circular bottom container containing the exemplary propane tank.

FIG. 34 is a first side view of section D-D of the gripping base and drip guard for circular bottom container containing the exemplary propane tank.

FIG. 35 is a front view of section D-D of the gripping base and drip guard for circular bottom container containing the exemplary propane tank.

FIG. 36 is a first perspective view of section D-D of the gripping base and drip guard for circular bottom container containing the exemplary propane tank; and,

FIG. 37 is a second perspective view of section D-D of the gripping base and drip guard for circular bottom container containing the exemplary propane tank.

All broken lines showing are included for the purpose of illustrating environment and forms no part of the claimed design.
